UNITED STATES PATENT OFFICE.

JAMES SCHEVENELL, OF NEW YORK, N. Y.

ANTIFRICTIONAL BINDING FOR COLLARS.

1,277,264.

Specification of Letters Patent. Patented Aug. 27, 1918.

Application filed February 12, 1918. Serial No. 216,830.

To all whom it may concern:

Be it known that I, JAMES SCHEVENELL, a citizen of the United States, residing at New York, in the county of New York and 5 State of New York, have invented certain new and useful Improvements in Antifrictional Binding for Collars; and I do hereby declare the following to be a full, clear, and exact description of the invention, such as 10 will enable others skilled in the art to which it appertains to make and use the same.

My invention relates to wearing apparel, and has reference to devices for reinforcing and lessening the friction of the edges of 15 fabrics, such as collars, whereby said edges are not only protected from contact with adjacent objects, but are rendered smooth and true so as not to have a wearing, or incisive, or abrasive action upon the proximate parts of garments.

As is well known, the edges of collars are roughened and hardened to a considerable extent when laundered, the result being that the necktie of a person who wears such collars is, in the course of time, worn or abraded by frictional contact with the edges 25 of successive collars. The object is, therefore, to overcome the wear which is due to this cause, and thus avoid, as far as possible, 30 the wearing out of neckties, which occurs not only when the neckties are being adjusted or tied, but when they are thrust against the edges of the collar during the ordinary movements of the person.

35 It will be understood that although my improved device is especially adapted for use with collars, cuffs or similar laundered articles, it is adapted for use as a binding for the edges of fabrics which are subject 40 to abrasion.

Figure 1, is a view representing the antifrictional binding, associated with means for securing it to a collar.

Fig. 2, is a view showing a section of the 45 collar and the binding.

Fig. 3, is a view in perspective showing the binding detached from the collar.

Fig. 4, represents a modification.

Fig. 5, is a perspective view of the binding 50 shown in Fig. 4.

Fig. 6, is a section taken on the line 6—6, of Fig. 4.

Fig. 7, is a view of a further modification.

Fig. 8, is a section taken on the line 8—8, 55 of Fig. 7.

Fig. 9, is a view of the binding shown in Figs. 7 and 8.

Fig. 10, is a view of the button cap of Figs. 8 and 9.

Fig. 11, is a view illustrating a further 60 form of fastening device, associated with a collar and binding.

Fig. 12, is a section taken on the line 12—12, of Fig. 11.

A, represents a collar of the usual type, 65 but it may be provided with stud holes, a, as shown in Figs. 6 and 8.

B, is a binding consisting of a stamped sheet of metal having flanges to receive between them the edge of a collar, as shown, 70 the narrow flange, b, being exposed at the margin of the collar flap, and the wider flange b¹, being concealed behind said flap. The flange, b¹, is extended beyond the quadrupled plies, b², of the collar, and is provided, 75 with a thickened or bent edge, b³, which engages behind the ridge formed by said plies. The flange, b, is deflected and curved to present a rib-like formation, and to cause its edge, b⁴, which may have a fold, 80 b⁵, to engage the collar. The binding may be co-extensive with the front edge of the collar flap, or it may be extended around the lower margin of the collar a desired distance, as shown in Fig. 4. The narrowness 85 of the flange, b, causes it to appear as a fine line of marginal ornamentation.

Figs. 4, 5 and 6, reveal an additional securing device which is a stud, C, adapted to be passed through the stud hole, a. This 90 stud has a male base, c¹, secured to the flange b¹, and a female cap, c, secured to the ear, b⁶, which extends inward from the flange, b, of which it is a continuation. The two parts, c, c¹, are adapted to snap together, the male 95 member being slotted, as shown, to give it resiliency. The ear, b⁶, is, for illustrative purposes, shown, in Fig. 5, as bent, so as to reveal the cavity in the female member, c. In Fig. 4, the binding is shown as continuing a short distance along the lower margin 100 of the collar.

Figs. 7, 8, 9 and 10, illustrate a modification of the binding wherein the flange, b¹, is provided with an ear, b⁷, to which 105 is attached the male member, c¹, of the stud, C. In this construction, the female member, c, is unattached, but when in use rests upon the surface of the collar, being then held in place by its engagement with the male mem- 110

ber, c^1 , which extends through the hole, a , in the collar.

Figs. 11 and 12, show a securing device which may be substituted for the securing device of Figs. 7, 8, 9 and 10. This device includes a lever, E , pivoted on an ear, D , extending inward from the flange, b , and provided with a cam, e , which in the position shown, bears upon and holds the collar within the binding. Release is effected by turning the lever and thus rendering the cam inactive.

The binding may be, and preferably is, composed of resilient metal, so that it may inherently operate to clamp the edge of a collar between its two flanges. If so constructed, and especially if the wider flange terminates in a thickened or folded edge which may engage behind the shoulder formed by the plies of fabric at the edge of the collar, additional securing means, such as I have described, may not be required.

The binding may be enameled for ornamental and protective purposes, and may be colored to harmonize with the apparel of the wearer, or according to the taste or fancy.

The binding may not be provided with the flange, b^1 , for it may be attached to a collar by a series of projections extending under the edge of the collar, and serving the same purpose as the said flange.

The binding may be formed by any of the known processes of metal working, as by the use of dies, and celluloid, paper, or paper reinforced by metal or other substance, in skeleton form, may be used in its construction.

Having thus described my invention, what I claim is:

1. An anti-frictional binding for collars, consisting of a suitably fashioned folded strip of metal, having the parts of a snap button secured to the respective flaps thereof.

Copies of this patent may be obtained for five cents each, by addressing the "Commissioner of Patents, Washington, D. C."

2. The combination with a fold-over collar having a stud hole in each of its outer folds, of a binding for each outer fold provided with securing means extending through said stud hole. 45

3. The combination with a fold-over collar having a stud hole in each of its outer folds, of a binding for each outer fold provided with a stud having a base and a detachable cap for securing said binding to the collar by the co-action of said stud and said stud hole. 50

4. An anti-frictional binding for collars, having a flange which is adapted to underlie the margin of a collar, said flange being thickened at its free edge, to engage the ridge formed by the manifoldest fabric at 60 said margin. 55

5. An anti-friction binding, adapted to embrace the edge of a piece of wearing apparel, and provided with a flange which is adapted to engage a ridge of said wear- 65 ing apparel.

6. An anti-frictional binding, having a folded edge adapted to engage a ridge in a piece of wearing material.

7. An anti-frictional resilient binding, 70 having flanges to secure said binding to the edge of a garment, one of said flanges having a shoulder at the free edge thereof for engaging a ridge of the fabric.

8. The combination with a collar having a 75 stud hole in each of its ends of a binding for each end, said bindings being each provided with a securing device for engagement with the adjacent hole.

9. A resilient binding for collars, having 80 a wide flange, a narrow ornamental rib, and securing means additional to said flange and rib having parts disposed on opposite sides of said binding.

In testimony whereof I affix my signature. 85
JAMES SCHEVENELL.
